(57) **CLAIM**

The ornamental design for an airway device, as shown and described.

DESCRIPTION

FIG. 1 is a top perspective view of an airway device showing our design;

FIG. 2 is a bottom perspective view thereof;

FIG. 3 is a right side plan view thereof;

FIG. 4 is a left side plan view thereof;

FIG. 5 is a front elevational view thereof;

FIG. 6 is a bottom plan view thereof;

FIG. 7 is a top plan view thereof;

FIG. 8 is a top perspective view of a second embodiment of our design;

FIG. 9 is a bottom perspective view thereof;

FIG. 10 is a right side plan view thereof;

FIG. 11 is a left side plan view thereof;

FIG. 12 is a front elevational view thereof;

FIG. 13 is a bottom plan view thereof;

FIG. 14 is a top plan view thereof;

FIG. 15 is a top perspective view of a third embodiment of our design;

FIG. 16 is a bottom perspective view thereof;

FIG. 17 is a top plan view thereof;

FIG. 18 is a right side elevational view thereof;

FIG. 19 is a left side elevational view thereof;

FIG. 20 is a back elevational view thereof;

FIG. 21 is a front elevational view thereof; and,

FIG. 22 is a bottom plan view thereof.

The broken lines in FIGS. 8-14 depict portions of the airway device that form no part of the claimed design. The broken lines in FIGS. 15-22 depict environmental subject matter and form no part of the claimed design.
